CLAIM

The ornamental design for a surgical suction tip, as shown & described.

DESCRIPTION

FIG. 1 is a top perspective view of a surgical suction tip showing our design;

FIG. 2 is a rear perspective view thereof;

FIG. 3 is a bottom perspective view thereof;

FIG. 4 is a top plan view thereof;

FIG. 5 is a right side elevation thereof, and left side view being a mirror image of the right side;

FIG. 6 is a bottom plan view thereof;

FIG. 7 is a rear elevation view thereof; and,

FIG. 8 is a front elevation view thereof.
